UNITED STATES PATENT OFFICE.

GUIDO ANTONI AND UGO ANTONI, OF PISA, ITALY.

BLADE PROPELLER FOR SUBMARINE BOATS.

1,411,769.

Specification of Letters Patent.

Patented Apr. 4, 1922.

Application filed March 11, 1915. Serial No. 13,675.

(GRANTED UNDER THE PROVISIONS OF THE ACT OF MARCH 3, 1921, 41 STAT. L., 1313.)

To all whom it may concern:

Be it known that we, GUIDO ANTONI and UGO ANTONI, both subjects of the King of Italy, residing at Pisa, in the Kingdom of Italy, have invented new and useful Improvements in Blade Propellers for Submarine Boats, (for which we have filed application in Italy March 13, 1914, Patent No. 141,327,) of which the following is a specification.

This invention relates to blade or fish tail propellers such as are more particularly adapted for use in connection with submarines, and the object of the invention is to improve the structure and shape of the blade propellers shown and described in our Letters Patent of the United States No. 1,050,090.

It has been found that while the rectangular and trapezoidal blades constructed in accordance with our aforesaid Letters Patent give very good results as regards the speed obtainable in raising or lowering a boat under the surface of the water they do not answer all practical requirements inasmuch as they are not conformed to resist the additional stresses arising when the boat is raised or lowered while it is being moved forward.

This disadvantage is obviated by the improved structure according to this invention.

In the accompanying drawings:

Figures 1, 2 and 3 are diagrammatic side views of blade propellers of the known type;

Figures 4 and 5 are similar views of blade propellers according to the invention.

Figure 1 shows a rectangular blade propeller having a section tapering from the lower edge toward the upper edge. The arrow A shows the direction of the thrust during the submerging of the boat, while the thrust of the screws which ensure the propulsion of the boat, is directed along B.

It is obvious that the leading edge C D of the blade has to overcome the resistance of the water and is therefore subjected to a greater stress than the other parts of the blade. Experiments have shown that when the boat is given a horizontal motion, the lines of deflection of the blade, that is to say the lines connecting the points corresponding to equal deflection of the blade, are not parallel to the axis or pivot

O of the blade (Fig. 1) but on the contrary they are situated on conical surfaces and give rise to a resulting force which brings about the submerging of the boat and has approximately the direction of the arrow R (Fig. 2), which is such that it counteracts the forward motion of the boat.

The dotted lines in Figure 1 represent the lines of deflection of the blade when the submerging takes place without longitudinal movement. Figure 2 illustrates the lines of deflection of the same blade when subjected to the resistance of the water due to the longitudinal movement of the boat. The convergence of the lines of deflection at D' gives rise to stresses which frequently cause the blade to break at that point.

In other known types of blade propellers the thickness of the blade not only decreases from the lowermost edge towards the uppermost, as in Figures 1 and 2, but also from the leading edge towards the following edge (section x—y, Fig. 3). But these blades of trapezoidal shape also do not give satisfactory results, firstly because great difficulties due to the nonuniform hardening of the steel in zones of varying thickness are encountered in the manufacture of such blades, and secondly because the simultaneous vertical and horizontal thrusts give rise to a component having approximately the direction of the arrow R' (Fig. 3) which causes the lines of deflection to converge at M and the blade to be liable to break at that point, as explained above with reference to point D' in Fig. 2. This action is still more marked when the boat is moved backwards.

The various requirements are all met by the propeller designed in accordance with this invention which is shown in Fig. 4 and comprises a blade having a curved leading edge extending rearwardly from the forward end of lowermost edge O to the uppermost edge C. As in Fig. 1 the cross section of the plate tapers from the lowermost edge towards the uppermost, but the longitudinal section B—B' shows a uniform thickness.

The improved blade can be obtained from a rectangular blade by taking away a substantially triangular zone F. The exact shape of the curve C D is determined by the speed of the ship. The contour is always so designed as to obtain the greatest rigidity at D, the elasticity of the blade in-

creasing gradually from D towards C; the successive horizontal sections are all of rectangular shape.

With this conformation the actions observed at D' (Fig. 2) and M (Fig. 3) no longer take place. Further the blade can be manufactured easily as all the sections parallel to the pivot have the same thickness and allow of a uniform hardening of the steel.

With this type of propeller forces may arise which may deflect the component toward the bow (see R', Fig. 4) during the submerging, but these forces are negligible. The form shown in Fig. 4 however does not allow of the boat being moved backwards without danger of breaking the blade near the edge H, L. When it is intended to provide for both forward and backward motion it is preferable to use a propeller such as shown in Fig. 5, which is symmetrical with respect to its middle axis A S, the area F and T on either side of the blade being equivalent. A propeller of this form will resist the stresses equally well when the boat is moving forward or backward.

Having thus described our invention and how the same is to be carried into practice, what we desire to protect by Letters Patent is:—

1. A flexible blade propeller comprising a blade supported along one of its edges and having a rectangular longitudinal section decreasing in length from the supported edge to the opposite edge.

2. A flexible blade propeller comprising a blade supported along one of its edges and having a rectangular longitudinal section decreasing both in length and width from the supported edge to the opposite edge.

3. A flexible blade propeller comprising a substantially wedge-shaped blade supported along its thick edge and having a longitudinal cross-section of uniform thickness and a width increasing gradually from one

end of said edge towards the middle of the blade.

4. A flexible blade propeller comprising a substantially wedge-shaped blade supported along its thick edge and having a longitudinal cross-section of uniform thickness and a width increasing gradually from both ends of said edge toward the middle of the blade.

5. A flexible blade propeller comprising a substantially wedge-shaped blade mounted to swing about its thick edge and having a curved leading edge extending rearwardly from the front end of the said thick edge to a point on the opposite edge substantially in the middle plane of the blade.

6. A flexible blade propeller comprising a substantially wedge-shaped blade mounted to swing about its thick edge and having curved front and rear edges meeting substantially in the middle plane of said blade.

7. A flexible blade propeller comprising a substantially wedge-shaped blade mounted to swing about its thick edge, said blade having a longitudinal cross-section of uniform thickness and a curved leading edge extending rearwardly from the front end of the said thick edge to a point on the opposite edge substantially in the middle plane of the blade.

8. A flexible blade propeller comprising a substantially wedge-shaped blade mounted to swing about its thick edge, said blade having a longitudinal section of uniform thickness and curved front and rear edge meeting substantially in the middle plane of said blade.

In testimony whereof we hereunto affix our signatures in the presence of two witnesses.

GUIDO ANTONI.
UGO ANTONI.
